EX

OF D 17,613

WILLIAM NIEMANN, OF CHICAGO, ILLINOIS, ASSIGNOR TO NIEMANN,
WEINHARDT & CO., OF SAME PLACE.

DESIGN FOR A CENTER-TABLE.

Design No. 17,613 dated August 9, 1887.

D17613

Elm Center Table. - No. 144. Size: 22x30.

UNITED STATES PATENT OFFICE.

WILLIAM NIEMANN, OF CHICAGO, ILLINOIS, ASSIGNOR TO NIEMANN,
WEINHARDT & CO., OF SAME PLACE.

DESIGN FOR A CENTER-TABLE.

SPECIFICATION forming part of Design No. 17,613, dated August 9, 1887.

Application filed July 5, 1887. Serial No. 243,466. Term of patent 3½ years.

To all whom it may concern:

Be it known that I, WILLIAM NIEMANN, a citizen of the United States of America, residing at Chicago, in the county of Cook and State of Illinois, have invented and produced a new and original Design for Center-Tables, of which the following is a specification, reference being had therein to the accompanying drawing.

10 The drawing represents a perspective view of my newly-designed center-table, in which A is the table-top, being rectangular with chamfered corners, each corner with a pendant, a, and with drapery-shaped strips b between said pendants. The legs C are turned on their upper portions, standing vertical, while their lower parts, forming the feet, are curved in an outward diagonal direction, each forming an ogee outline. A shelf, D, is framed 15 between the legs C just above the curved por-

tions thereof, and this shelf D has upon its edges shallow railings d, each composed of an upper and a lower bar connected by inclined strips.

I claim--

25 The design for a center-table herein shown and described, the same consisting of a rectangular table-top, A, having chamfered corners, each with a pendant, a, and with drapery-shaped strips b, four vertical legs, C, having 30 ogee-curved feet extending outward in diagonal directions, and between such legs a shelf, D, with a railing, d, consisting of parallel bars connected by inclined strips or bars.

In testimony whereof I affix my signature in presence of two witnesses.

WILLIAM NIEMANN.

Witnesses:

WILLIAM H. LOTZ,
OTTO LUBKERT.
